UNITED STATES PATENT OFFICE.

PETER M. CARMICHAEL, OF NEW YORK, N. Y.

MAGAZINE FUSE PLUG.

1,426,040.

Specification of Letters Patent. Patented Aug. 15, 1922.

Application filed June 12, 1920. Serial No. 388,502.

To all whom it may concern:

Be it known that I, PETER M. CARMICHAEL, a citizen of the United States, residing at New York city, in the county of New York,

5 State of New York, have invented certain new and useful Improvements in Magazine Fuse Plugs; and I do hereby declare the following to be a full, clear, and exact description of the invention, such as will enable others skilled in the art to which it ap-

10 pertains to make and use the same.

This invention relates to improvements in electric fuses and particularly to magazine fuses.

15 One object of the invention is to provide a novel and simple device of this character which can be screwed into the socket of a junction box, in the manner of the ordinary fuse plug, and when one of the fuses burns out it is only necessary to rotate a certain part of the plug to bring into play a new fuse, thus obviating the usual procedure of removing the fuse and placing a new one in the socket.

20 25 Other objects reside in the peculiar construction and arrangement of the various parts whereby the desired results are obtained.

In the drawing:

30 Figure 1 is an elevation of a fuse made in accordance with my invention;

Figure 2 is a bottom plan view of the rotary plug;

35 Figure 3 is an enlarged vertical section on the line 3—3 of Figure 1;

Figure 4 is a top plan view of the device with the rotatable plug removed.

Referring now to the drawings, the present plug comprises a porcelain body 10, 40 having a circumscribing flange 11 at one end and the upper portion of which flange is slightly enlarged as shown at 11^a and knurled as illustrated, to facilitate screwing and unscrewing of the plug. The opposite end portion of the plug body is reduced in diameter as shown at 11'. Upon the body portion 10 is fitted a metallic sleeve 12 in which are pressed the usual threads 13 to engage the threads of the socket into which 45 50 the plug is to be screwed, this sleeve 12 being flanged inwardly at its lower end as shown at 12' against the corresponding portion of the body 10.

Through the upper end of the body 10 is 55 formed a cavity 14, the upper portion of which is countersunk with a resultant

shoulder 15 and within the countersink and upon this shoulder is disposed a plug disk 16, also of porcelain or other suitable insulating material.

About the body portion 10 and directly adjacent the flange 11, there is formed a circumscribing groove 17 and the sleeve 12 above referred to, projects upwardly so as to enclose the lower portion of this channel, as 60 65 clearly illustrated in Figure 3.

Formed through the flange 11 of the porcelain is an annular series of cylindrical passages 18, which annular series is coaxial with the body 10 and these passages have their 70 lower ends directly above the upper edge of the sleeve 12. The passages lead through the shoulder 15 at the bottom of the countersink of the cavity 14. Leading inwardly and radially from each cylindrical passage 75 18 is a channel 18' formed in the shoulder 15, and each of these channels 18' communicates with a groove 19' formed longitudinally of the wall of the cavity 14. A plurality of fuse wires 19 are provided, each of inverted 80 U-shape.

Each fuse wire 19 is disposed with one leg in a groove 19', and with its other leg in a passage 18, while its communicating or bight portion is disposed in the corresponding channel 18'. The leg in the passage 85 18' is longer than the other leg and continues downwardly into the channel 17 where it is soldered or otherwise electrically connected with the sleeve 12. On the under side of the disk 16, and extending from the 90 center to the edge thereof is a brass spring bar 21. The inner end of this bar has an eye loop 22 in which is connected the upper end of a helical spring 23, said spring extending down through the cavity 14 and 95 through an opening 24 in the lower portion of the plug where it is connected to a metal contact member 25. This member is disposed centrally on the inner end of the plug and is adapted to contact with the spring in the 100 center of the ordinary socket. The outer face of the disk is provided with a knob 26 by means of which the disk may be rotated.

The disk 16 is provided with an index 30 on its upper face, while upon the flange 11 105 and over each of the fuse wires is marked a number as indicated. The index 30 is directly over the contacting spring 21 so that the spring will make contact with that fuse wire whose number is opposite to the index.

110 In operative position, the outer end of the member 21 is in metallic contact with

the portion of one of the fuse wires 19 that lies in a channel 18' so that current will pass from the member 25, through the spring 23, the member 21, one of the fuse wires 19 and the metallic sleeve. Should the fuse wire burn out, it is only necessary to rotate the disk 16 so as to bring the outer end of the member 21 in contact with the outer end of another fuse wire, the contact 10 25 rotating with the spring and the disk 16. In order to prevent the flash of a burning fuse wire from affecting adjacent wires, the face or shoulder 15 is provided, intermediately of the grooves or slots 18', with 15 the radially extending shoulders or ribs 27, said ribs 27 providing dividing walls between the several fuses. The cap disk 16 is provided with correspondingly formed radial grooves or recesses 28 which fit over 20 the ribs 27 when the cap disk 16 is lowered into position with the contact strip 21 in engagement with one of the fuses. Thus when the active fuse blows out, the danger of its affecting any of the adjacent fuses is 25 obviated. The interfitting elements 27 and 28 also provide a means for accurately positioning the contact strip 21 over any one of the fuse wires. The spring 23 exerts a constant pull upon the cap disk 16, to seat 30 the latter and also to hold the contact strip in engagement with the fuse wire. Therefore, if it is necessary to rotate the disk to position the contact strip over a new fuse wire, the cap is lifted against the action of 35 the spring 23 to disengage the elements 27 and 28, after which the cap disk may be rotated to the desired new position and re-seated in contact with a new fuse wire.

To protect the spring 23 against the heat 40 from the melting fuses, a cylindrical casting 21' of any suitable insulating refractory material may be disposed over it.

What is claimed is:

1. An electric fuse plug comprising a 45 body having socket engaging contacts and channels leading to one of them, fuse wires disposed in the channels and connected with the contact to which the channels lead, the body having also radial ribs alternating 50 with the fuse wires, a rotatable cap for the body having radial grooves disposed to receive the ribs respectively and separate the fuse wires, a contact carried by the cap and rotatable therewith into engagement 55 with the fuse wires successively, and a

resilient conducting element connected between the last named contact and with the socket engaging contact to which the fuse wires are not connected and under the influence of which resilient member the cap is held yieldably with the ribs in the grooves. 60

2. An electric fuse comprising a hollow body having an overhanging portion and 65 a plurality of channels formed through said overhanging portion, a metallic sleeve surrounding the hollow body, fuse wires extending through the channels and connected to said sleeve, a cap disk rotatably seated 70 in the top of the hollow body, a contact member carried by the cap disk, means for resiliently holding the cap disk in its seat, and radially extending ribs on the body 75 alternating with the channels, the cap disk having grooves corresponding to the ribs and adapted to receive them, the ribs constituting guard members between successive fuse wires and holding the cap disk against rotation when engaged in the 80 grooves.

3. An electric fuse plug comprising an insulating body having a circumscribing flange at one end and having its other end reduced in diameter, the body having also 85 a circumscribing groove directly adjacent the flange and having also a cavity in one end that is countersunk, and having channels formed radially of the bottom of the countersink and passages leading from the 90 outer ends of the channels to the said circumscribing groove, a threaded sleeve disposed upon the body and extending part way over the circumscribing groove, a fuse disposed in each channel and passage and 95 electrically connected with the sleeve, a disk rotatably mounted in the countersink and having a contact disposed to engage the fuses successively when the disk is rotated, 100 a contact member carried by the reduced end of the body and a resilient conductor between the said contacts disposed to hold the disk yieldably with the first-named contact to engage the fuses in the different positions of the disk. 105

In testimony whereof, I affix my signature, in the presence of two witnesses.

PETER M. CARMICHAEL.
